BRUSH AND BEATER ROLL FOR
VACUUM CLEANERS

Frank Oren Skidmore, Cuyahoga Falls, Ohio

Application January 25, 1949, Serial No. 72,683

1 Claim. (Cl. 15—5)

1
This invention relates to sweeper rollers for use with electric vacuum sweepers, especially to the particular type of beater element used on such sweeper rollers.

One of the best known types of sweeper rollers used on vacuum cleaners at the present time is that shown in Patent No. 1,918,432 wherein a plurality of resilient brush members are carried by the roller and a beater member also extends spirally around the surface of the roller. This beater member is of a rigid, inflexible construction and its size must be carefully controlled since, among other reasons, the rigid beater member, if too large, would produce undesired vibration and also it might tear or produce appreciable wear on the surface of a rug when used. Of course if the rigid beater element were too small, then it would have no beneficial beater action. In all events, it is difficult to obtain the maximum beating action desired under different operating conditions by the use of a rigid beater member. Hence numerous efforts have heretofore been made to provide a more flexible or yielding beater element which could then be of a larger size than the rigid element heretofore used. These flexible beater members usually have been of such a construction or have been secured to a sweeper roller so that they would be flexible only in one direction and frequently have used some type of a pivoted connection to the roller by which yielding movement in one direction can be obtained. Thus to secure the desired yielding action, such means must be used or rotated in one predetermined direction. Other types of beaters heretofore proposed have suggested the use of resilient rubber beaters. Such resilient beaters have poor aging properties and are of relatively weak construction or are light in weight so that they do not form a desired beater or do not give proper action. Likewise the flexibility of same may give them a relatively poor beater action.

It is the general object of the present invention to avoid and overcome the foregoing and other difficulties with previous types of sweeper beaters and to provide a novel, effective sweeper beater which is characterized by the uniformity and efficiency of the beater action obtained regardless of the direction of rotation of the roller on which the beater is positioned.

Another object of the invention is to provide a hinged type of a beater for a sweeper roller wherein the beating action is improved by providing a concentration of weight in the free edge portion of the beater member.

2

Another object of the invention is to provide a relatively inexpensive, uncomplicated type of a beater member for a sweeper roller wherein the beater member is adapted to give a long service life with a minimum of maintenance.

Another object of the invention is to provide a sweeper roller with a pivotally mounted solid beater element adapted to provide an automatic, efficient beating action by centrifugal forces regardless of the direction of rotation of the sweeper roller.

The foregoing and other objects and advantages of the invention will be made more apparent as the specification proceeds.

5 Attention is now directed to the accompanying drawings wherein one embodiment of the invention is illustrated in detail, and wherein:

10 Fig. 1 is an elevation, partially broken away and shown in section, of the head portion of a vacuum cleaner showing a sweeper roller positioned therein;

15 Fig. 2 is an elevation of the sweeper roller of Fig. 1 separate from the remainder of the mechanism; and

20 Fig. 3 is a vertical cross sectional elevation taken on line 3—3 of Fig. 2 but with only one beater member being shown in the section and with the remaining beaters of the sweeper roller being eliminated for clarity.

25 In describing the present invention, corresponding reference numerals will be used in the drawings and in the specification to indicate corresponding parts.

30 Now referring to the details of the structure shown in the drawings, a conventional electric vacuum sweeper head or operative section 1 is shown which is carried by a plurality of wheels 2 and includes a sweeper roller indicated generally by the numeral 3. A flexible drive belt 4 is engaged with the sweeper roller 3 for rotating or driving same and this belt 4 is driven by conventional means (not shown) whereby the sweeper head can be used to pick up dirt and other debris on the surface over which the head 1 is moved.

35 Fig. 2 best shows the sweeper roller 3 and indicates that a plurality of sweeper bristles 5 are secured in any conventional manner to and extend from the periphery of a cylindrical member, or support sleeve 6 which forms the frame of the sweeper roller 3. Usually the bristles 5 are arranged in a plurality of groups or tufts which extend substantially helically across the surface of the support sleeve 6. In this instance, two series of bristle tufts are provided on spaced longitudinal portions of the support sleeve 6.

40 **45** **50** **55** Usually a center, annular recess 7 is provided

in the surface of the support sleeve 6 for engagement with the drive belt 4.

An important feature of the invention resides in the particular type of beater element provided in the sweeper roller 3. These sweeper beaters are shown as comprising a plurality of substantially rigid or inflexible beater elements or plates 8. The beaters 8 are shown as having a plurality of hinged eyelets 9 formed integrally therewith and in spaced longitudinal relation along one edge of the beater 8. At the other edge, or free edge of the beater, the metallic plate used in forming the beater is curled back around upon itself to forming a substantially tubular end section 10 for the beater so that the free edge portion of the beater is of relatively heavier unit area construction than is the remaining portion of the beater. Such a construction facilitates the beater action obtained by use of centrifugal forces exerted on the beater element of the invention. In some instances, it may even be desirable to add extra weight elements or means to the beater at or adjacent the free edges thereof to achieve this desired construction. It also should be noted that the external surfaces of the beater elements adjacent the edges 10 thereof are of relatively smooth contour and this again facilitates and aids in obtaining smooth engagement between the beaters and any carpet or other article with which the beaters are associated for cleaning same.

As another salient feature of the present invention, the beaters 8 are adapted to be pivotally secured to the support sleeve 6 for pivotal movement of substantially 180 degrees in extent. To this end, a plurality of support plates 11 are secured to the surfaces of the support sleeve 6 by cap screws 12 with the support plates 11 being spaced longitudinally of the sweeper roller 3 and being also spaced from each other around the circumference of the support sleeve 6. Fig. 2 shows that a plurality of hinged eyelets 13 are formed along one edge of each of the support plates 11 in longitudinally spaced relationship to each other whereby a conventional hinge pintle 14 may be engaged with each associated pair of hinged eyelets 9 and 13, which are formed complementary to each other whereby the beaters 8 can be pivotally secured to the individual support plates 11. It should be noted that the longitudinal axes of the hinge pintles 14 and of the beaters and support plates are arranged parallel with the longitudinal axis of the support sleeve 6. Flat portions 15 are angularly staggered in helical relationship to provide recesses in the roller member 6 to receive the support plates 11, as indicated in Fig. 3. The angle of the helix of the recess is substantially the same as the angle of the helix of the tufts 5.

It will be realized that the support sleeve 6 can be secured to the head 1 in any desired manner and shaft means 16 are shown provided on the sweeper roller for journaling same on the head 1.

From the foregoing description it should be readily apparent that the beaters 8 will automatically be flung outwardly by centrifugal force when the sweeper roller 3 is rotated by the belt 4. Furthermore, regardless of the direction of rotation of the sweeper roller 3, the beaters 8 will be adapted to be swung outwardly therefrom and give a desired beating action for material contacting the sweeper roller. It also should be

noted that the beaters extend farther from the surface of the support sleeve than do the bristles 5 in this embodiment of the invention.

The plates 8 may be made from any desired material but usually are metallic to give desired beating action and a long service life. The beaters may be arranged in any desired manner on the surface of the sleeve 6.

The support sleeve 6, or roller member of the sweeper roller, may be formed from any suitable material and its position with relation to the surface of the article being cleaned need not be as carefully controlled as if a fixed beater member were used. Of course the sweeper roller may be used on any kind of a cleaning device that is powdered in any desired manner, even to being manually operated.

While one complete embodiment of the invention has been disclosed herein, it will be appreciated that modification of this particular embodiment of the invention may be resorted to without departing from the scope of the invention as defined by the appended claim.

Having thus described my invention, what I claim is:

In a sweeper, a cylindrical roller member, said roller member having a plurality of longitudinally spaced flat portions providing recesses on the outer periphery thereof, said flat portions being angularly staggered in a substantially helical relationship, helically arranged rows of bristle tufts secured to the roller member and extending radially therefrom, the angle of the helix of the recesses being substantially equal to the angle of the helix of the tufts, a plurality of support plates, one of the plates being secured to the roller member in each of the recesses whereby the support plates are secured substantially within the outer circumference of the roller member, eyelets integrally formed in spaced relationship along one edge of each support plate, a plurality of beater plates, eyelets integrally formed in spaced relationship along one edge of each beater plate, and a plurality of hinge pintles, a pintle being secured in said eyelets for hingedly engaging a beater plate to each support plate, said eyelets and pintles being axially parallel to the longitudinal axis of the roller member, the free edge of each beater plate parallel to the pintle being rolled to form a substantial tubular section of a length substantially equal to the length of the pintle.
